United States Patent Office.

CHARLES D. F. SMITH, OF GENEVA, ILLINOIS.

Letters Patent No. 82,761, dated October 6, 1868.

IMPROVEMENT IN STOVE-DRUMS.

The Schedule referred to in these Letters Patent and making part of the same.

TO ALL WHOM IT MAY CONCERN:

Be it known that I, CHARLES D. F. SMITH, of Geneva, in the county of Kane, and State of Illinois, have invented a new and useful Improvement in Stoves and Furnaces; and I do hereby declare and make known that the following is a full, clear, and exact description of the same, reference being had to the accompanying drawings, and to the letters and figures marked thereon, which form part of this specification.

My said invention relates to that class of stoves and furnaces designed for heating purposes, in which the fire-chamber is surmounted by a vertical drum or chamber and a surrounding cylinder, leaving an annular space between, in which space a spiral inclined flue is constructed, through which the heat and smoke from the fire or combustion-chamber pass circuitously and spirally upward around the said central chamber before entering the pipe or chimney, for the purpose of producing a more complete and perfect radiation of the heat.

The great objection to stoves of this character, heretofore, has been the impossibility of regulating or diminishing the radiation of the heat at such times and under such circumstances as such decrease or diminution of heat would be desirable; and the nature of my invention consists in a novel mode of constructing the aforesaid spiral flue surrounding the central air-drum, whereby a direct draught can be produced up through the annular space occupied by said spiral flue at pleasure, in order to diminish the quantity of heat radiated, when desired.

To effect this object, I construct the aforesaid flue, or the spirally-arranged plate which forms said flue, in sections, each section being supported or hung upon a pivot or bearing, so as to be movable at pleasure, whereby it may be turned or arranged so as to form part of the spiral inclined plane forming said spiral flue, or so turned up in a vertical position as to afford a direct vertical draught through the aforesaid annular space.

To enable those skilled in the art to understand how to construct and make use of my said invention, I will proceed to describe the same with particularity, making reference in so doing to the aforesaid drawings, in which—

Figure 1 represents a central vertical section of my invention.

Figure 2 is an enlarged view, showing one of the vertical series of sections of the spiral inclined plane forming the circuitous flue.

Figure 3 is a horizontal section through the air-drum and outer cylinder, showing a plan of the sectional inclined plane; and

Figure 4 is an enlarged detail plan view of one of said sections, showing its pivoted bearings or journals.

Similar letters of reference in the several figures denote the same parts of my said invention.

A represents the fire-chamber; B, the outer cylinder; C, the inner or air-chamber; E, the air-flues, to conduct or admit air from without to the central drum; and D represents the spiral inclined plane, arranged within the annular space between the cylinder B and the air-chamber C, as shown, to form the aforesaid spiral flue from the fire-chamber around the air-chamber to the chimney or pipe.

The said inclined plane D is made up of a series of quadrantal sections, as indicated in the drawings, each separate section being marked D in figs. 2, 3, and 4, and being provided at each end with projecting lugs or bearings, which enter suitable recesses in the cylinder B.

These sections are arranged so as to present four vertical series, which vertical series are all connected by a rod or bar, as clearly shown in fig. 2.

By this arrangement, upon turning a rod or knob attached to one of each vertical series of sections, the entire series may be turned, so as to occupy their normal positions as parts of the inclined spiral forming the circuitous flue, or, when desired, may be turned up vertically, so as to give a direct vertical draught.

The sections of said inclined spiral plate may be quadrantal or semicircular, or be formed of greater or less angle than the right angle, provided there be regular vertical series to be operated, as described.

Or, if desired, the spiral inclined plane may partly be permanently fixed in place between the drums B C, having a single series of vertical movable sections, so that a vertical direct draught might be obtained at one side through the openings formed by turning up such movable sections.

When the entire inclined spiral is made in movable sections, so as to operate as aforesaid, the tipping up of said sections has the additional effect of thoroughly cleaning out the said spiral flue, which cannot be effected in flues of the ordinary construction in heaters of this kind.

When only a vertical series of movable sections is made, as above mentioned, even then the process of cleaning out may be partially effected, the soot being removed entirely from the movable portions of the flue, and to some extent from the stationary parts, by the action of the draught passing up and eddying between the stationary plates forming the stationary portions of the flue.

Having described the nature, construction, and operation of my invention, I will now specify what I claim, and desire to secure by Letters Patent.

I claim constructing the inclined plane, forming the spiral flue, around a central drum, cylinder, or reservoir, wholly or in part in sections, susceptible of being adjusted to form a continuous circuitous spiral flue; or to open vertically and permit a direct vertical draught, substantially as and for the purposes set forth and described.

CHAS. D. F. SMITH.
